UNITED STATES PATENT OFFICE

THOMAS SCOTT GRIEVE, OF LEICESTER, ENGLAND

KNITTING MACHINE

Application filed September 29, 1928, Serial No. 309,167, and in Great Britain May 7, 1928.

This invention comprises improvements in or relating to knitting machines and has reference to machines of the double or superposed cylinder type adapted for the production of ribbed fabrics.

An object of the present invention is to provide in this class of machine means for enabling an extensive range of patterns and pattern effects to be produced.

10 The principal feature of the present invention consists in effecting the selective sliding displacement of the needles in either or both cylinders of a double or superposed cylinder knitting machine by the provision of sliders associated with said needles or on jacks co-acting with said sliders of a plurality of spaced butts and cams adapted selectively to engage with said butts.

Another feature of the invention consists 20 in the employment in a machine as above of plural butted sliders or jacks and cams selectively engaging with said butts for effecting the transfer of selected needles from one cylinder to another.

25 A further feature of the invention which is obtained as a result of the selective transfer of the needles resides in the production on a double or superposed cylinder machine of ribbed fabric in which the nature of the 30 rib can be varied at any predetermined knitted course.

Yet another feature consists in the employment in a machine of the type referred to of plural butted sliders and a plurality of cams for selectively engaging with said butts so as to cause selected needles in either or both cylinders to take thread from one or more of a plurality of yarn feeds in each 40 knitted course and thus produce plated patterns in the fabric.

For the purpose of more fully describing the nature of this invention, reference will now be made to the accompanying drawings 45 wherein:—

Fig. 1 is a cross-sectional elevation through the needle cylinders of a circular knitting machine of the superposed cylinder type, showing one method of applying the 50 present invention.

Fig. 2 illustrates a type of needle and slider employed in this invention.

Fig. 3 illustrates an alternative form of slider and a jack for co-acting therewith.

Fig. 4 is a diagrammatic view illustrating 55 the relative positions of certain of the parts of the machine with which this invention is concerned.

Fig. 5 is a fragmental plan view illustrating part of one of the needle cylinders, a 60 particular arrangement of sliders therein, hereinafter described, and a selector cam for co-acting with said sliders.

Fig. 6 is a detail end elevation of a selector cam in engagement with the slider 65 butts.

Fig. 7 is a diagrammatic view of a particular arrangement of sliders, co-acting jacks and cams, hereinafter described, and

70 Figure 8 is a side elevational view of the machine, taken at a right angle to Figure 1, and showing the control drum and selecting levers.

In carrying out the invention a machine of the known type is employed having two superposed needle cylinders 1 and 2 in axial alignment fitted with double-ended needles 3 for the production of ribbed fabric, certain of the needles operating in one cylinder and the remainder in the other cylinder. As is 75 usual in this type of machine, within the tricks 4 in each cylinder above and below the needles are fitted sliders 5 adapted to engage the needle hooks, and in order to transfer needles from one cylinder to the other, say 80 from the upper to the lower cylinder, the upper sliders are released from the upper needle hooks and the lower sliders are hooked on to the needles and operated by a cam device to draw down the needles.

85 All of the sliders are provided with a knitting butt 5^a, for engagement by the usual knitting cams diagrammatically indicated by the numeral 16 in Figure 1, and in a preferred embodiment of the present invention all or 90 certain of the sliders in either or both cylinders are also provided with one or more additional butts 5^b, suitably positioned along the slider.

95 A plurality of thread feeders as shown dia- 100

grammatically at 17 in Figure 1 of any convenient known type are installed, one adapted to supply a ground or body thread to the needles and another a plating thread, the plating feeder being disposed higher than the ground feeder in the customary manner, and in order to permit of the needles being variably selected to take plating thread, a plurality or series of selector cams 6, is employed exterior to either or both needle cylinders so as to coact with the aforesaid additional butts 5^b, on the sliders prior to the needles taking their thread.

These selector cams 6, conveniently comprise plunger members 6^a, mounted one above another to slide in a suitable bracket 7, radially of the machine, said plungers being disposed in horizontal alignment with the additional butts 5^b, on the sliders 5, and each plunger being adapted to be pressed inwardly towards the sliders against spring resistance by pivoted lever mechanism operable from a suitably driven rotating pattern wheel, chain or the like 8. On this pattern wheel or drum 8, is a series of projecting butts or cam pieces 9, which cam pieces are arranged in circumferential rows on the drum. With each row of cam pieces a pivoted crank arm 10 coacts, said arm when displaced by engagement with a cam piece effecting, through suitable links or levers 11, the displacement of a further pivoted arm 12, formed with a hollow boss or sleeve 13, within which is slidably mounted a spring pressed pin 14, a bevelled nose 14^a, on said pin being adapted to coact with one of the aforesaid spring pressed plungers 6^a, terminating in a selector cam and causing said cam to engage with certain of the butts on the sliders registering therewith so as vertically to displace the sliders.

It will be understood that the number of plungers or selector cams 6, coincides with the number of pivoted members 10, operated from the pattern wheel or drum 8.

Although, as has been previously stated, sliders 5, having pattern selection butts 5^b, a battery of plunger cams 6, and means for selectively operating same, may, if desired, be provided in connection with either or both needle cylinders of the machine, it is preferable to provide same in connection with the bottom cylinder 2 only, and to select the needles to produce plated patterns in the fabric after all of said needles have been transferred 55 to the lower cylinder to produce plain, i. e. unribbed fabric.

In this preferable application of the invention, the operation is such that all needles are caused by the usual stitch cams to take thread 60 from the ground feeder, and only those needles selected by the aforesaid selector cams 6, coacting with the additional butts 5^b, on the sliders are raised to a higher position to take the plating thread, a pattern being thus 65 produced the nature of which is determined

by the arrangement of the cam pieces 9 on the pattern drum or wheel 8, acting upon the spring influenced selector cams 6, in conjunction with the disposition of the slider butts 5^b.

If desired the thread feeders may be constructed and operated by any convenient means so as to enable the relative positions of same to be reversed, thereby causing the thread previously used as a ground thread to become a plating thread and vice versa.

If desired, instead of providing the additional butts 5^b, as aforesaid on the sliders said butts may be provided upon separate jacks 15, see Fig. 3, operating in the needle tricks and co-acting with said sliders, and where such separate jacks are employed a suitable cam 16 is conveniently provided ahead of the selector cams 6, see Fig. 7, to co-act with butts on the sliders so as to depress or move those sliders selected at any knitted course and their coacting jacks into a position to be re-selected by the said cams 6.

If desired, certain of the needles may be provided with co-acting sliders having additional integral butts 5^b, and the remainder provided with sliders of the usual type (see Fig. 3) adapted to be selectively operated by the jacks 15.

The nose portions of the selector cams for engagement with the slider or jack butts are suitably inclined or diagonally disposed to effect the requisite sliding motion of the sliders or jacks. Should however the end faces of a selector cam come into engagement with a slider butt before such butt has reached a position to enable same to ride over an inclined face of the selector cam, the sliding pin which presses against and effects inward movement of the selector cam is depressed against its spring 14^b thus enabling said inward movement of the selector cam to be retarded and prevent any possibility of the slider butt becoming fractured or damaged.

A further or alternative precaution against damaging the slider butts when introducing the selector cams and means whereby a selector cam may be introduced definitely at a predetermined needle are illustrated in Fig. 5. At that particular needle where a selection is to commence the slider appertaining thereto and a plurality of adjacent sliders to be selected may be provided with butts 5^c longer than the remaining butts 5^b provided at the same height on the other sliders, such an arrangement allowing the selector cam 6 to be introduced just prior to the leading long butted slider, at which the selection is to commence being brought into contact with said cam. Upon the sliders having long butts 5^c engaging with the cam, they are caused to be raised and ride over an inclined face of the cam, as illustrated in Fig. 6, which then moves forward to its full extent to engage all the butts provided on the sliders at that height. In this manner end thrust on the

slider butts by the cam 6 when the said cam is being introduced is eliminated and definite selection, commencing at any predetermined needle, is assured.

5 If desired, the butts upon the sliders or jacks may be of varying lengths, to enable an increased range of patterns to be obtained, in which case the cam pieces on the pattern drum or wheel are of varying heights so as to 10 press the selector cams in to varying distances to select a greater number of combinations of sliders and needles.

When employing a slider having additional patterning butts 5^b, in conjunction with each needle, the selection of the needles to produce plated patterns may be effected by first raising all needles to the plating height, i. e. the height whereat selected needles take the plating thread, and then, by means of the cams 6, selectively lowering those needles which are to take the ground thread only, just prior to the needles reaching the feeding position.

In cases where several adjacent or successive needles remain unselected and only take the ground thread, thus forming comparatively long loose or float threads on the rear face of the fabric, any suitable known means may be incorporated whereby one or more of such needles may be operated to produce a tuck stitch or stitches, thus binding said float thread to the web.

In lieu of or in addition to the before-described selector cams for producing patterns in the fabric a plurality of transfer cams of similar construction may be provided in connection with either or both of the needle cylinders adapted to coact with butts as before described on the sliders or jacks so as to raise or lower selected needles from one cylinder to the other to transfer same. By this means it will be appreciated that a predetermined variation can be obtained in the rib of the fabric by selectively transferring the needles.

45 Briefly therefore it may be said that according to this invention pattern effects are produced by actuating selected needles either by virtue of such needles taking thread different from or additional to those taken by the non-selected needles and/or by virtue of such needles being transferred from one cylinder to another. In the appended claims where the context so permits the expression "pattern" is held to include patterns produced by both these means; that is to say, pattern produced by yarn variation or stitch variation.

The one or more batteries of cams 6, for displacing selected needles to produce plated or variable ribbed effects in the fabric are preferably positioned as indicated at "A" in Figure 4 before the stitch cams indicated at "B", and after the transfer return cam indicated at "C" at which position the said cams may engage with the pat-

tern butts 5^b on the sliders 5 or jacks 15, prior to said sliders reaching the usual stitch cams "B". The transfer return cam "C" returns all needles transferred at "A" to the top cylinder to the bottom cylinder to be re-selected prior to the knitting of the next course. In Fig. 4, the needle cylinder is represented by the circle "D" and rotates in the direction of the arrow.

The invention is particularly applicable for use in connection with a machine having rotating needle cylinders and stationary thread feeds, but it will be appreciated that same can readily be applied to a machine in which the needle cylinders are stationary and the feeds rotate. In the latter case means will of course have to be provided for mounting the aforesaid selector cams and operating means therefor so as to rotate around the needle cylinders.

It is to be clearly understood that in the appended claims where the context so permits the term "slider" is to be interpreted broadly as covering a slider of the one-piece type as illustrated in Figure 2, or a slider and coacting jack, which together constitute a divided slider, as illustrated in Figure 3.

FIG. 3.

Claims:

1. A circular knitting machine comprising a pair of superposed needle cylinders, needles slidably mounted therein, sliders co-acting with said needles, a knitting butt on said sliders, a thread feeding device, stitch cams for engaging said knitting butts, a plurality of patterning butts on said sliders, a plurality of selector cams for selectively engaging with said patterning butts to effect selective sliding displacement of the needles, a bracket for supporting said selector cams in a superposed manner, concealed means for returning each of said latter cams to its normal position after same has been displaced, a plurality of bell crank levers, a sleeve portion formed on each of said levers, a spring influenced plunger member provided within each of said sleeve portions, said plunger members actuating the selector cams, pivoted links connecting said bell crank levers to further bell crank levers, and a pattern control device actuating said latter levers to effect selective operation of the needles.

2. A circular knitting machine comprising a pair of superposed needle cylinders, needles slidably mounted therein, a thread feeding device, sliders co-acting with said needles, a knitting butt on each of said sliders, stitch cams engaging said knitting butts, a plurality of spaced pattern butts on said sliders, a plurality of radially slidably spaced pattern cams normally retained in their outermost position by spring means associated with each of said cams, an independent bell crank lever associated with each of said pat- 120 125 130

tern cams, a hollow cylindrical housing on each of said bell crank levers, a spring pressed plunger provided within each of said housings, a rod connecting each of said bell 5 crank levers to a further bell crank lever, a rotating pattern drum selectively operating said bell crank levers and capable of moving, through the intermediary of said levers, any one of said pattern cams into engagement with the said pattern butts independently of the remainder of said pattern cams and selecting any desired combination of said pattern cams for engagement with said pattern butts to effect an 10 extensive selection of the needles for sliding displacement.

3. A circular knitting machine comprising a pair of superposed needle cylinders, needles slidably mounted therein, sliders co- 15 acting with said needles, a knitting butt on each of said sliders, a thread feeding device, stitch cams engaging the knitting butts on the sliders, a plurality of independent pattern butts on said sliders, a plurality of 20 superposed pattern cams for engaging said pattern butts, springs for normally retaining said cams inoperative, spring pressed plungers for operating said pattern cams, pivoted levers carrying said plungers, and 25 pattern control mechanism for operating said levers.
